STAMP ALBUM OR THE LIKE

Silvio Pinto, New York, N. Y.

Application January 30, 1941, Serial No. 376,593

3 Claims. (Cl. 129—20)

The present invention relates to improvements in photographic albums, stamp albums, scrap books, or the like wherein it is desired to mount or secure for display purposes, objects of monetary or sentimental value, and to protect the photographs, stamps, manuscripts, or the like, from the effects of atmosphere, damage due to handling, and to minimize the loss of the mounted objects through pilfering.

It is an object of the present invention to provide improved album means wherein objects such as stamps, photographs, or the like, may be mounted for display, said album embodying improved pocket means for the reception and retention of the objects.

It is a further object of the invention to provide an improved album page of laminated construction, wherein the principal laminations of heavy durable sheet material forming the obverse and reverse sides of the page are combined with another lamination composed of smooth transparent material, the latter forming a window behind which the mounted object may be viewed, and so arranged with respect to such principal laminae as to protect the stamp or like displayed object from abrasive contact during insertion or removal of the objects.

Album pages provided with pockets for the protected display of stamps or the like are known to the art. Certain of such prior art devices, however, are characterized by pockets of Celluloid or the like which do not lie flat against the principal surface of the page, thus being subject to tearing; and others possess the disadvantage that the stamps or like objects are subjected to abrasive contact with the materials comprising the album page, when the objects are inserted into or removed from the display pockets.

A feature of the present invention lies in the disposition of smooth, transparent, material such as cellulose acetate in such manner that it provides a facing for the relatively rough material of the page lamination with which the stamp or other object would otherwise come into contact during the insertion or removal thereof.

Such arrangement of a cellulose acetate sheet or the like pursuant to the present invention makes it possible to employ stiff, durable materials for the principal laminations of the album page, and to die cut or otherwise form flaps in one of such laminations which, by reason of the resiliency of the material, will be normally self-closing even after frequent use, and will lie in the principal plane of the album.

Other features and advantages will hereinafter appear.

In the accompanying drawing:

Figs. 1 and 2 are respectively, an obverse and reverse view of an album page embodying the invention, such album page contemplating window means whereby a displayed object may be viewed on both of its sides;

Fig. 3 is an enlarged section taken through 10 3—3 of Fig. 2 illustrating the access openings and a portion of the pocket afforded by the laminations of such page;

Fig. 4 is a front view of a portion of an album page embodying yet another form of the invention; and

Fig. 5 is an enlarged section taken along the line 5—5 of Fig. 4.

Referring to the drawing, my improved album page 10 is of laminated construction, comprising 20 principal laminations 11 and 12, respectively forming the obverse and reverse faces of the album page, and one or more intermediate laminations 14, the latter preferably being of suitable smooth, transparent, material such as cellulose acetate, glassine paper, etc. Such laminations are suitably secured to provide pockets for the reception of photographs and the negatives thereof, stamps, etc.

Laminations 11 and 12 may be of heavy bond 30 paper or equivalent material affording strength and durability. It is a feature of the invention that regardless of the possibly abrasive quality or rough texture of the bond paper or the like, the photographic negative or the picture surface 35 of a photograph, stamp, or the like, is protected from contact with such possibly abrasive material during the insertion or removal of the article from the album pocket, by suitable disposition of the smooth-surfaced cellulose acetate, etc., forming the lamination 14, with respect to such possibly abrasive laminations 11 and 12.

As indicated, the outer sheet or lamination 11 is cut to afford window means, said window means being "glazed" by the smooth, transparent, sheet 14. The respective laminations 11, 12, 45 14, may be secured by adhesive, suitably applied to form marginal areas wherein the three laminations comprising the sheet are mutually secured. It will be noted that the invention contemplates that the frontal and rear laminations 50 11, 12, respectively of the album leaf are to be adhesively joined throughout the complete periphery thereof, to prevent any separation of the laminations about the edges of the album sheet 55 through handling or other normal usage, and

that the lamination 14 extends up to and beyond the access opening provided by the flap 17.

The inherent stiffness of the preferred material for the lamination 12 insures that the flaps 17 provided therein will normally lie in the plane of the lamination and thus the album page is devoid of raised portions which may be "caught," and thus possibly torn, during the normal handling of the page. The configuration of the flap 17, as will be seen from Fig. 3, is such that the upper edge of the lamination can be, and would be in the normal use of the album, brought outwardly in hinge fashion, to provide a funnel-like mouth for the insertion of the stamp or photograph.

The album page specific to Figures 1 through 3 represents an embodiment of the invention wherein both sides of the article to be mounted may be of importance, and wherein it may be desirable to protect both surfaces of the object from abrasion, as aforesaid.

In such construction, both of the principal laminations 11, 12 of the album sheet are die cut in mutual registry to provide suitable window openings, and a double inner lamination 14 is provided, each such lamination 14 being adhesively secured to its respective principal lamination. As is clearly apparent from Figure 3, the laminations 14 are so disposed with respect to the therewith associated paper lamina as to substantially completely cover any surfaces of the bond paper or like relatively stiff material with which the article will come in contact when being inserted into the album pocket.

Pursuant to the principles set forth above, one of the principal laminations may be die cut to provide a flap 17 lying normally in the plane of such lamination, it being understood that the outward curvature of the flap 17 shown in Fig. 3 is an indication merely of how such flap is manually displaced preliminary to the insertion of the object. The inherent resiliency of the material forming such principal lamination causes the flap 17 to resume its normal substantially flat status after the object is inserted.

In the embodiment shown in Figures 4 and 5, it will be noted, see Figure 5, that the lubricous transparent lamination 14 may be adhesively secured to the outer lamination 11 subsequently to the die cutting of the window apertures in such lamination, but prior to the die cutting of the flaps 17, thus insuring that the full surface of the flap 17 is covered by a lubricous, non-scratching material. When the stamp or like object is inserted into the pocket, it appears that the outer, delicate surface of the stamp or the like will be in contact only with the smooth lamination, and will be protected from any contact with the outer album lamination.

It will thus be seen that my invention provides for the use of stiff materials suitable to withstand the treatment given an album, such as thumbing the pages, or the like, and that the selection of suitable material for the album pages is broadened by the fact that a strong paper or like material may be selected notwithstanding that it may have an abrasive surface which may be per se detrimental to a fine surface of a photograph, or the delicate coloring or marking of a stamp or the like.

Additionally, the invention achieves the advantages of transparent pockets for the reception of stamps or the like, while providing for substantially wholly flat page surfaces devoid of projecting elements or unprotected edge surfaces which

may be defaced or torn during the normal use of the album.

The normally closed access flaps render petty thievery or pilfering of the displayed objects difficult, by making positive physical effort necessary to move the flaps 17 out of their normally closed position to afford access to the stamps or like objects.

Whereas I have described my invention by reference to specific forms thereof, it will be understood that many changes and modifications may be made without departing from the spirit of the invention.

I claim:

1. An album page for the protected display of stamps, photographs or like objects having a picture or principal surface, comprising: a laminated sheet including principal laminations forming obverse and reverse sides of said album page and an intermediate lamination of a transparent, smooth character, said laminations being mutually secured about their respective peripheries and mutually secured at other areas to define individual pockets for the reception of said objects behind said transparent, smooth lamination; one of said principal laminations having apertures formed therein to afford display of such objects and cut to form flaps through which cuts the objects may be slid into said pockets; said transparent, smooth lamination being adhesively secured to said flaps, whereby upon inserting an object into a pocket of said album page through the entrance provided by said flap the picture or principal surface of such object is in contact only with the surface of said smooth lamination.

2. An album page for the protected display of objects such as stamps, photographs and the like, comprising: paired and mutually secured laminated sheets, each consisting of a sheet of relatively stiff material to which is adhesively secured a lamination of smooth, transparent material; said paired laminated sheets being mutually secured to define pockets for the reception of such objects, each of the outer relatively stiff sheets being formed with mutually registering apertures exposing said transparent laminations in the areas of said pockets, whereby objects within said pockets may be viewed from both sides; one of said pair of laminated sheets being cut to form a flap through which cut an object may be slidably inserted into a pocket, the inner surface of said flap and all surfaces in contact with which the displayed object comes during the stage of insertion into or removal from said pocket being of said smooth, transparent material.

3. An album page for the protected display of objects such as stamps, photographs and the like, comprising: a laminated sheet including principal laminations forming obverse and reverse sides of said album page and an intermediate lamination of a transparent, smooth character, said laminations being mutually secured about their respective peripheries and mutually secured at locations within such peripheries to define individual pockets for the reception of such objects behind said transparent, smooth lamination; one of said principal laminations having apertures therein affording display of such objects; the second principal lamination having flaps and adjacent slits through which the objects may be slid into said pockets, each flap being formed by a long slit disposed outside of the boundaries of said aperture and an angularly related slit connecting with said long slit at each end thereof, said angularly related slits extending in the di-

rection of said aperture to provide, when said flap is opened, a mouth extending in the direction of insertion of said object into said pocket and of such area of opening that no edge of the flap-provided lamination or surface of the flap contacts the picture surface of the object during the stage of insertion of the object into the

5 pocket; the relationship of said transparent, smooth lamination to said principal laminations being such that during the insertion of an object into a pocket, a face of such object adjacent the flap is in contact substantially only with the smooth, transparent lamination.

SILVIO PINTO.
